LINE GUIDE

Julius Lemperle, Salt Lake City, Utah

Application September 23, 1940, Serial No. 357,893

3 Claims. (Cl. 120—33)

My invention relates to line guides and copy holders and has for its object to provide a new and highly efficient line guide for use by Line-a-time or Linotype operators or for any other use where it is desired to read a single line and which it is desired to completely set out from the rest of the page.

A further object is to provide an adjustable line guide for fine or heavy type so that the guide having parallel spaced apart line rules may be separated or drawn closer together if desired to place one rule along each side of the line of printing being copied or read.

A still further object is to provide a line guide which may be attached to the usual copy finger of all Intertype or Linotype machines and used in conjunction therewith, the movable part being adjustable by a cam action to grip the walls of the slotted head of the stationary head of the lower side to permit spacing the two rods apart as desired.

A still further object is to provide a line guide which may be attached to the guides used by stenographers and the like and used in the same manner, the vast difference being that the line above and below the line being copied will be covered thereby eliminating any possible chance of error.

A still further object is to use the guide on books having very fine print to enable a person reading the book to concentrate on the single line facilitating the reading of fine print on either side.

These objects I accomplish with the device illustrated in the accompanying drawing in which similar numerals and letters of reference indicate like parts throughout the several views and as described in the specification forming a part of this application and pointed out in the appended claims.

In the drawing,

Figure 1 shows the use of my device attached to a copy holder for typists or printers, parts cut away.

Figure 2 shows a side elevation of Figure 1.

Figure 3 is a plan view of the device removed from any holders showing the main essential features.

Figure 4 is an inverted view of Figure 3.

Figure 5 is an edge view of Figure 4.

Figure 6 is an edge view of the device attached to a copy holder paper clamp.

Figure 7 is a plan view of Figure 6.

In the drawing I have shown a copy table as A, having a stand B on which it is adjustably

mounted by wing nuts and bolts at the heads of spaced apart legs C of the stand B. The table A is provided with the usual vertical rod 5 spaced from the table A by the ends 6 being bent back and secured to the table in the conventional manner.

Onto this rod 5 I mount my line guide which consists of a finger clamp D attached to the rod 5 by the guide cylinder 7 on the back side or stationary part of the finger clamp D. Thus, the clamp and guide may be raised and lowered on the rod 5.

The guide of my invention consists mainly of a lower guide bar 10 having an L head 11 on the end thereof and which bar is beveled along the upper edge adjacent the copy paper to provide ruled spaces 12 for guiding printers and type setters in their work.

The head 11 is slotted at 13 and the adjusting feature of the device is carried in said slot 13. The head 14 of the upper guide bar 15 is formed as a channel enclosing the face, one edge, and part of the back on one side and the other edge of the head 11 of the bar 10. This provides vertical movement of the upper guide bar 15 relative to the lower guide bar 10. The adjustment is provided by a finger nut 16 attached to a rotatable shaft having the end enlarged and formed oblong in that portion thereof which is carried within the slot 13. Thus, by turning the finger nut 16, the oblong portion will grip the side walls of the slot 13, locking the upper guide bar 15 spaced any desired distance from the guide bar 10. The head 11 is provided with spaced apart holes 19 to permit attachment of the head to any Line-a-time, Intertype, Linotype or other similar devices securing the spaced guide bars to the sliding head of any of these machines which use a copy holder on a copy holder table. A screw 21 is screwed into the end of the oblong area of the finger nut 16 to hold the nut in place.

It will also be obvious that the same type of a device may be made to attach the device over the reading surface of a newspaper, book, or the like, just so long as a vertical rod is provided to hold the line guide bars parallel to the reading matter, and such modifications and variations are considered a part of my invention and within the scope of the claims.

Having thus described my invention I desire to secure by Letters Patent and claim:

1. A line guide comprising a lower bar having an L-shaped head; another bar mounted on the L-shaped head, said latter bar being verti-

cally adjustable on said head to space the bars apart any desired distance.

2. A line guide comprising parallel guide bars one of which is adjustably mounted on the other to provide an adjustable space between the two bars to permit adjusting the two bars to a width to encompass any size of type to be copied. 5

3. A line guide comprising parallel guide bars, one of which has the other adjustably mounted thereto to provide for adjustment of the said one bar to vary the space between said bars.

JULIUS LEMPERLE.
